ROBERT C. MATHEWS, OF WYOMING, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed January 10, 1928. Serial No. 245,647.

This invention relates to telegraph signaling systems adapted for high speed transmission.

An object of the invention is to improve 5 the accuracy of operation of repeating or receiving systems of the type in which a vibrating relay arrangement controlled by a rotary distributor is employed for regenerating impulses of unit length which have 10 been lost in transmission.

According to the present invention this object is attained by connecting the incoming line to a pair of condensers through a synchronously operated rotary distributor 15 in such a manner that the two condensers are alternately charged by successive line current impulses, the value of each charge corresponding to the area under the line current curve for a selected fraction of a 20 line current impulse interval. By selecting a fraction of the current impulse interval the effects of line distortion are minimized. While one condenser is being charged, the other is discharging in a circuit extending 25 through the relaying or repeating means and one of a second pair of condensers. The condensers of the second pair which are also alternately charged, but from a local source of energy, are charged by 30 means of the vibrating action of a pair of relays connected to the rotary distributor and discharged simultaneously with the first pair of condensers through the common discharge circuit, only one condenser 35 of each pair being discharged at one time. Inasmuch as the charges on the condensers, discharging simultaneously, may be of opposite polarities, the charge having the higher value will control the operation of 40 the relaying or repeating means and in this manner alternating impulses of positive and negative current are furnished to operate the relaying or repeating means in place of the successively transmitted single 45 unit line impulses which are lost by attenuation in attaining high speed transmission.

This invention contemplates a telegraph system in which a vibrating relay arrangement is automatically maintained in synchronism with the transmitting and receiving mechanisms, or more specifically, the frequency of vibration of a vibrating relay arrangement is under the control of a receiving distributor, which in turn, as in 50 standard multiplex printing telegraph sys-

tems, is automatically maintained in synchronism with the transmitting distributor.

A system in accordance with the invention comprises a pair of condensers connected directly to the line through a synchronously operated rotary distributor, a pair of vibrating relays synchronously operating with the rotary distributor and a second pair of condensers connected through the contacts of the vibrating relays 60 to a local source of battery for inserting current impulses of unit length to replace those which are greatly attenuated in transmission over a cable.

The above and other objects and advantages of the invention are set forth in the following description which may be more readily understood if considered in conjunction with the accompanying drawing.

The drawing illustrates the receiving apparatus at station X which is connected by a cable 10 to a distant station (not shown). Each station is provided with a special rotary distributor connected to the cable through a receiving condenser 11 shunted by 70 a resistance 12 or other form of distortion correction network, the input and output circuits of a space discharge or other type of amplifier 13 and a conductor 14. This distributor is arranged to rotate in synchronism with other distributors connected to the cable in accordance with practice well known in the art. Of the distributor at station X the receiving face only is shown and this face comprises seven ring sets 75 15 to 21, inclusive, shown in part only as representing sectors A to F for six successive impulse intervals, it being required for the proper operation of the system that the receiving face have an even number of sectors. The time intervals for the signal impulses are each broken up into three parts corresponding to the sub-sectors A₁, A₂, A₃, B₁, B₂, and B₃, etc. and each part shall be approximately one-third of the total length 80 of a single time unit, although it is desirable in most cases to make the central part of each signal unit as short as compatible with the speed and steadiness of operation of the relays which are used in the receiving circuit. The operating functions of the A and B intervals are cyclically repeated, C interval corresponding to A, D to B etc. Brushes 85 22 to 28, inclusive, are arranged to rotate in contactual engagement with ring sets 15 to 100 110

21, respectively, and in such a manner that they establish contacts with their respective ring sections within each signal interval simultaneously. Polarized relays 29 to 32, 5 inclusive, are biased in the manner shown and are arranged to be momentarily operated by alternate currents of positive and negative polarities interspersed with periods of no current, by the rotation of brush 23 over ring set 16. The operating action of these relays is such that when brush 23 picks up positive current, the armatures thereof are actuated to their left or S contacts and when the brush picks up negative current 10 the armatures are actuated to their right or M contacts. It follows then that the armatures of relays 29 and 32 are on their S contacts during the time intervals A_1 and A_2 , and on their M contacts during the time intervals A_3 , B_1 , B_2 and B_3 and that the armatures of relays 30 and 31 are on their M contacts during intervals B_1 and B_2 and on 15 their S contacts during the intervals A_1 , A_2 , A_3 and B_3 . The relays are similarly 20 affected as the brush 23 rotates through sector pairs C and D and E and F, etc.

Ring set 15 receives the incoming signal impulses from conductor 14 and the central portion of each impulse impresses a charge 25 as brush 22 rotates over ring set 15 on one or the other of two condensers 33 and 34 which are arranged to be alternately charged through the operation of relays 29 and 30. These condensers are further arranged to 30 discharge alternately, but through the operation of relays 31 and 32, the discharge being effected through a circuit extending through a local amplifier 35 and a receiving relay 36 and a second pair of condensers 37 35 and 38 during the time that brush 26 is rotating over segments corresponding to the central parts A_2 , B_2 , etc. of the signal intervals. Relay 36 is of the unbiased polarized 40 type and is responsive to only those charges 45 on condensers 33 and 34 that are stored by incoming signal impulses of two or more units length, the charges on condensers 37 and aiding in operating the relay during the intervals in which condensers 33 and 34 are 50 discharging the low voltages stored therein by the incoming signals of unit length. The operation of relay 36 closes a circuit extending from either the positive or negative pole 55 of battery 39, depending upon the polarity of the incoming signals, to recorder 40.

Condensers 37 and 38 are arranged in a 60 vibrating relay circuit comprising ring sets 20 and 21, relays 41, 42 and 43, potentiometer 45 and local battery 39, and the charges thereon are referred to herein as local 65 charges. It will be well to note at this point that when the incoming signals are of unit length the charge stored on either of condensers 37 and 38 will always be opposite in polarity to that stored simultaneously on

either of the line condensers 33 or 34 and therefore the simultaneous discharge of a line and a local charge in series through a common circuit, aid in operating relay 36. But when a line signal of two or more units 70 length is received the charge on the line condensers becomes strong and the condensers receiving the second impulse of the signal will be charged with a potential of the same polarity as the condenser receiving the first 75 impulse, and therefore in accordance with the alternate arrangement of condensers 37 and 38 one of the latter condensers will receive a charge from battery 39 which is now 80 of the same polarity as the charge on the line condenser, corresponding to the second impulse of the signal. In the simultaneous discharge of these charges of like polarity the charge on the line condenser being considerably stronger will predominate and therefore hold the armature of relay 36 in the position in which it was last moved. Relay 36 will thus be maintained in one position 85 for a duration of a long signal and the polarity of the alternate charges on condensers 37 90 and 38 will remain unchanged in the interim.

The vibrating relay circuit is connected to the operating circuit of relay 36 through the 95 contacts of the polarized relay 43 which operates simultaneously with relays 29 to 32 and therefore impulses generated in the vibrating circuit are impressed on the operating circuit of relay 36 in synchronism with the incoming signal impulses and aid in operating the receiving relay during those intervals in which single unit signals of alternating polarity are being received. Vibrating relays 41 and 42 are alternately operated 100 as the brushes 27 and 28 rotate over their respective ring sets 20 and 21 and thereby 105 alternating on condensers 37 and 38 impulse charges of a polarity corresponding to that of the last impulse relayed to recorder 40 by receiver relay 36.

Before beginning with the detailed description of the operation of the arrangement shown on the drawing it will also be well to note that the ring sets 15 to 21 are 110 concentric rings and are, for the sake of clearness, shown on the drawing as developed. The ring sets each consist of two rings, one of which is continuous and the other segmented, the segments being so arranged in each ring set as to provide the 115 proper sequence of operation in the receiving circuit. Ring set 15 which is connected to the line provides in its segmented ring three segments for each signal impulse interval and these segments are arranged so 120 that the middle or second segments receives the signal impulse at its greatest amplitude, the first and third segments being left dead. Ring 16 has its segmented ring divided into 125 two segments for each signal interval, one 130

having a length of approximately two-thirds of the interval and the other of approximately one-third, the long segment being connected to battery and the short segment being left dead. The long segments are alternately connected to opposite poles of battery 44 for the purpose of alternately connecting condensers 33 and 34 to the line. The segmented ring of set 19 is divided into alternately arranged 10 long and short segments, the short segments having a length approximately that of the middle part of the signal impulse incoming from the line and arranged in radial alignment with the live or signal segments of ring set 15, the long segments which have a length of approximately twice that of the short segments being left dead. The short segments of set 19 are provided to allow condensers 33 and 34 to alternately discharge 15 through the windings of relay 36, the discharge of one condenser being effected at a time when the other condenser is being charged over ring set 15 by the next incoming impulse. The segmented rings of ring 20 sets 17 and 18 are similar in that both serve the same purpose, that is, to effect the complete discharge of condensers 33 and 34 before a second charge can be stored on either condenser. Inasmuch as the condensers 33 25 and 34 are alternately discharged, the discharges of each are effected in alternate signal intervals and consequently the segmented rings of ring sets 17 and 18 are arranged as shown, so that condenser 33 effects its complete discharge during the third part of one signal interval and condenser 34 effects its complete discharge during the third part of the next signal interval. The segmented rings of ring sets 20 and 21 are also similar 30 to each other in that they likewise serve the one purpose, that is, to effect the alternate operation of relays 41 and 42 which control the charges on condensers 37 and 38. Inasmuch as condensers 37 and 38 discharge 35 simultaneously with the condensers 33 and 34, respectively, it is necessary that condensers 37 and 38 be charged in alternate signal intervals. Therefore, the segmented arrangements of ring sets 20 and 21 are each 40 provided with a live segment in alternate signal intervals, the live segments in one ring set being located in different signal intervals than those in the other, so that one or the other of relays 41 and 42 will be operated in each signal interval.

For the purpose of describing in detail the arrangement shown on the drawing, it is assumed that the distant station is transmitting a message comprising one positive, two negative, one positive and one negative impulse and that the first signal impulse is received at a time when brushes 22 to 28 are entering sector A. It is further assumed that the signal transmitted just preceding the above 45 signal combination was a negative impulse

of two or more units length and that therefore condenser 34 contains a strong charge of negative potential and condenser 37 contains a local or comparatively weak charge of positive potential, the charge on condenser 34 being sufficiently strong to operate relay 36 to its M contact when brush 26 rotates through sector A. The first live segment engaged by any of the brushes is the first long one in ring set 16, which is engaged by 50 brush 23. This segment is connected to the positive pole of battery 44 and immediately upon the establishment of the contact between the brush and segment polarized relays 29 to 32 and 43 operate to the position 55 shown in the drawing and condenser 33 is connected to ring set 15 in preparation for the first incoming signal, which is of positive current. As brush 22 passes from sub-sector A, and rotates over the segment in 60 sub-sector A₂, a light positive charge is stored in condenser 33. While brush 22 is rotating over the segment in sector A₂, brush 26 is rotating over the first short segment 65 shown in ring set 19 and thus completes the discharge circuit of condenser 34. The armature of relay 41 is at this time in its normal position and therefore brush 26 also completes the discharge circuit for condenser 37. The discharges of condensers 34 70 and 37 aid in operating receiving relay 36 to its M contact, thereby generating a signal of negative current for the recorder 40 which signal is representative of that transmitted from the distant station just previous to the 75 above signal combination. At the end of sub-sector A₂, brush 23 passes off the long segment of ring set 16, thereby disconnecting positive battery from relays 29 to 32 and 43 and the armatures of relays 29 and 32 are 80 actuated to their respective contacts M. At the same time, condenser 33 having been charged by a weak impulse of positive current is disconnected from the line as brush 22 disengages its associated segment in 85 sub-sector A₂. The brushes now enter sub-sector A₃ and brush 28 effects the operation of 90 vibrating relay 41 which moves its armature into engagement with its right-hand contact. The armature of relay 36 being in engagement with its M contact causes a negative charge from battery 39 to be stored in condenser 38, the charge being regulated by 95 potentiometer 45 to be of such a value as to operate relay 36 in conjunction with the weak 100 positive charge on condenser 33 when both condensers later on discharge simultaneously through the windings of the relay. Brush 25 in rotating through sub-sector A₃ 105 closes a circuit extending over contact M 110 of relay 32, through condenser 34 to ground, which circuit effects the complete discharge 115 of the heavy negative potential on condenser 34.

As the brushes enter sub-sector B₁, relay 120

41 being of the polarized biased type returns to normal and brush 23 engages a segment connected to the negative pole of battery 44. Relays 29 to 32 and 43 are therefore 5 upon energized, and relays 30 and 31 actuate their armatures to their respective M contacts. The brushes then proceed to sub-sector B_2 , whereupon brushes 22 and 26 close effective circuits, the former connecting condenser 34 to the line over closed contact M of relay 30 and the latter connecting condenser 33 to the local amplifier 35 of relay 36 over closed contact M of relay 31. While condenser 34 is being charged 10 by the second incoming signal with an impulse of negative current, condenser 33 with its weak positive charge is discharging through the winding of relay 36. Relay 43 having actuated its armature to its M contact during interval B_1 now allows condenser 38 to discharge its negative potential simultaneously with the discharge of the positive potential on condenser 33 and these charges 15 aid in operating relay 36 to move its armature to its S contact, thereby recording a signal of positive current in recorder 40. The movement of the armature of relay 36 may be determined by the direction of the 20 current in the discharging circuit as indicated by the arrows on the resistance 46 bridged across the input terminals of amplifier 35, a downward direction signifying that the armature engages the S contact, 25 and an upward direction signifying an engagement with the M contact. When the brushes reach the end of sub-sector B_2 the negative charge on condenser 34 has reached a higher value than the positive charge received by condenser 33 during the interval 30 A_2 , because as stated above, the second signal impulse is followed by another impulse of like polarity and consequently both impulses attain a greater amplitude than the impulse for the first signal which was of 35 unit length. When the brushes enter sub-sector B_3 the negatively charged condenser 34 is disconnected from the line, and negative battery 44 is disconnected from relays 40 29 to 32 and 43, whereupon relays 30 and 31 return their respective armatures to their S contacts. The return of the armature of relay 31 to its S contact at this time connects condenser 33 to ground through brush 36 45 and the condenser is drained of any residual charge. Brush 27 connects ground to the circuit extending from battery through the winding of relay 42 which causes relay 42 to operate and close its left- 50 hand contact, thereby establishing the circuit for impressing a positive charge on condenser 37. When the brushes reach the end of sub-sector B_3 , the armature of relay 42, which relay is also of the polarized biased type, returns to its normal position. 55

In sub-sector C_1 brush 23 again connects the positive pole of battery 44 to the windings of relays 29 to 32 and 43. Relay 29 operates to connect condenser 33 to the line in preparation for the third incoming signal. Relay 32 operates and inter-connects its armature and S contact in preparation for the discharge of the strong negative potential on condenser 34, and relay 43 operates and interconnects its armature and S contact to prepare for the discharge of the local positive potential on condenser 37. As the brushes proceed through sub-sector C_2 , the line is connected through brush 22 to condenser 33 which now receives the third incoming signal or the second negative charge of great amplitude. Simultaneously, brush 26 completes the discharging circuit prepared at the armature and S contact of relay 32, so that the negative charge on condenser 34 and the positive charge on condenser 37 may discharge simultaneously through the windings of relay 36, the charges again aiding, but in a direction (indicated as upward in resistance 46) to cause the operation of relay 36 to engage its M contact, thereby generating an impulse of negative current for the recorder 40. At the end of sub-sector C_2 , brush 23 disconnects relays 29 to 32 and 43 and the armatures of relays 29 and 32 return to their M contacts. In sub-sector C_3 brush 25 completes the discharge of condenser 34. Brush 28 causes relay 41 to operate, thereby allowing condenser 38 to be charged with negative potential. 100

In sub-sector D_1 negative current from battery 44 energizes relays 29 to 32 and 43 and the armatures of relays 30, 31 and 43 are actuated to their M contacts. Condenser 34 is connected to the line in preparation for the next or fourth incoming signal and condenser 33 is connected to the ring set 19 to prepare the circuit for the discharge of its negative potential. When the brushes enter sub-sector D_2 , brush 22 completes the line circuit to condenser 34, which is now charged by a weak impulse of positive current and brush 26 completes the discharging circuit of condenser 33. At this time relay 42 is in normal condition and the armature and contact M of relay 43 are closed, thereby allowing condenser 38 to discharge simultaneously with condenser 33. Condenser 33 being charged negatively and to a higher value than the negative charge on condenser 38 predominates in the discharging circuit and the current flows through resistance 46 in an upward direction, which causes relay 36 to move its armature to its M contact, thereby generating a signal of negative current for the recorder 40. The brushes upon leaving sub-sector D_2 cause a deenergization of relays 29 to 32 and 43 and the armatures of relay 30 and 31 re- 115 120 125 130

- turn to their S contacts, thereby disconnecting condenser 34 from the line circuit and preparing condenser 33 for its complete discharge to ground. The brushes proceed 5 through sub-sector D_3 , wherein brush 24 effects the complete discharge of condenser 33 and brush 27 causes the momentary operation of relay 42 thereby charging condenser 37 negatively from battery 39.
- 10 At the beginning of sub-sector E_1 , brush 23 causes positive current from battery 44 to again energize relays 29 to 32 and 43 and the armatures of relays 29, 32 and 43 move to their S contacts, thereby connecting condensers 33 and 34 to the ring sets 15 and 19, respectively. In subsector E_2 , brush 22 causes condenser 33 to be negatively charged by the fifth incoming signal, which being of unit length is relatively weak and brush 26 15 completes the discharging circuit for condensers 34 and 37. The negative charge on condenser 37 and the weak positive charge on condenser 34 aid in operating relay 36 and the direction of current through resistance 46 being in a downward direction causes the armature of the relay to engage its S contact to send an impulse of positive current to the recorder 40. The brushes then proceed into sub-sector E_3 , wherein the armatures of relays 29 and 32 return to their M contacts to disconnect condenser 33 from the line circuit, connect condenser 34 to ground and operate relay 41 momentarily to allow a local charge of positive potential 20 to be stored on condenser 38.
- In sub-sector F_1 , relays 29 to 32 and 43 are again energized by negative current from battery 44 and the armatures of relays 30, 31 and 43 are actuated to their respective M contacts, thereby connecting condensers 33 and 34 to ring sets 19 and 15, respectively. When the brushes enter sub-sector F_2 , condenser 34 is charged by the sixth incoming signal which is assumed herein 25 to be of positive polarity in order that the fifth and last impulse of the combination selected for the purpose of describing the invention, may be of unit length. The weak negative charge on condenser 33 discharges simultaneously with the positive charge on condenser 38 through the winding of relay 36 in a direction which actuates the relay armature to its M contact, thereby sending negative current from battery 39 to the recorder 40 to record the fifth signal. It will be noted that the brushes have passed over six sectors of the distributor and only five signals have been recorded. This is explained by the fact that the recordation of 30 the incoming signals is effected in the intervals immediately following those in which they are received at the distributor.
- In this manner signals are recorded at the receiving station in the same wave form as they were transmitted from the distant

station, a wave form of each recorded signal extending over the full length of a signal interval, but out of phase with the incoming signal wave by one interval due to the time constant of the receiving apparatus. It is obvious from the previous description that the present invention provides a system in which signal impulses of unit length will have no appreciable effect on the receiving relay 36 because of the attenuation characteristic of the cable, but other signal impulses representing such unit signal impulses will be repeated or relayed from a local source into the receiving circuit by a pair of condensers arranged to be alternately charged and alternately discharged in synchronism with the transmitting and receiving synchronous distributors. However, when signal impulses of two or more units length are received, another pair of condensers are alternately arranged to receive these signals in the form of a relatively heavy charge and these charges are alternately discharged through a common circuit simultaneously with the charges on the first mentioned pair of condensers and being of a higher value predominate in operating the receiving relay.

What is claimed is:

1. A telegraph system comprising a line terminating in a rotary distributor, a pair of condensers arranged to be alternately charged by line current impulses, a second pair of condensers arranged to be alternately charged during successive line impulse intervals and relaying or repeating means, characterized in this that the condensers of each pair are alternately discharged through a circuit common to the members of each pair, one condenser of each pair being discharged simultaneously and the predominating charge of the condensers discharging at the same time controlling the operation of said relaying or repeating means.

2. A method of relaying or repeating telegraphic signals in a high speed transmission system which consists in storing current charges corresponding in polarity to the impulses received from the line and balancing such charges against other charges stored synchronously with the charges from the incoming line impulses, said other charges being effective to operate relaying or repeating means when the first mentioned charges are ineffective to operate said means.

3. A method of relaying or repeating telegraphic signals in a high speed transmission system which consists in storing on a plurality of condensers current charges corresponding in polarity to the impulses received from the line and balancing such charges against other charges on a second group of condensers which are controlled by a vibrating device operating synchronously

with incoming line impulses, the latter charges being effective to operate said relaying or repeating means when they are higher in value than the charges furnished by the incoming line impulses.

4. A method of relaying or repeating telegraphic signals in a high speed transmission system which consists in storing on a pair of condensers current charges corresponding in polarity to the impulses received from the line and balancing such charges against charges on a second pair of condensers which are controlled by a pair of vibrating relays operating synchronously with the incoming line impulses, the latter charges being effective to operate said relaying or repeating means when they are higher in value than the charges furnished by the incoming line impulses.

5. In a telegraph system, an incoming line, a rotary distributor arranged to receive signal current impulses from said line, means for storing impulses incoming from said line, a local source of energy, other means for storing electrical impulses received from said local source of energy in synchronism with the incoming line impulses, a circuit extending through said distributor for discharging both of said means simultaneously, and means in said circuit arranged to be controlled by the higher current value of the impulses discharging simultaneously.

6. In a telegraph system, an incoming line, a rotary distributor arranged to receive signal current impulses from said line, a plurality of condensers arranged to be charged alternately through said distributor in response to signal impulses, a local source of energy, a second group of condensers arranged to be alternately charged from said local source of energy, a circuit common to

both of said groups of condensers for discharging a condenser of each group simultaneously, and relaying or repeating means in said discharging circuit arranged to be controlled by the predominating charge of the condensers discharging at the same time.

7. In a telegraph system, an incoming line, a rotary distributor arranged to receive signal current impulses from said line, a pair of condensers arranged to be charged alternately through said distributor in response to signal impulses, a local source of energy, a second pair of condensers arranged to be alternately charged from said local source of energy, a circuit common to both of said pairs of condensers for discharging a condenser of each pair simultaneously, and relaying or repeating means in said discharging circuit arranged to be controlled by the predominating charge of the condensers discharging at the same time.

8. In a telegraph system, an incoming line, a rotary distributor for receiving signal current impulses from said line, a pair of condensers arranged to be alternately charged in response to signal impulses, a pair of vibrating relays connected to said distributor and arranged to operate alternately during successive signal intervals, a local source of energy, a second pair of condensers arranged to be alternately charged by said local source of energy by the operation of said vibrating relays, and a circuit comprising relaying or repeating means for simultaneously effecting a discharge of a condenser of each of said pairs, the predominating charge on the condensers discharging at the same time controlling the operation of said relaying or repeating means.

In witness whereof, I hereunto subscribe my name this 4th day of January, 1928.

ROBERT C. MATHES.
